W. T. JANNEY

CENTRIFUGAL CASTING MACHINE

Filed Sept. 9, 1922

Patented Nov. 4, 1924.

1,514,319

UNITED STATES PATENT OFFICE.

WALTER T. JANNEY, OF PHILADELPHIA, PENNSYLVANIA.

CENTRIFUGAL CASTING MACHINE.

Application filed September 9, 1922. Serial No. 587,111.

To all whom it may concern:

Be it known that I, WALTER T. JANNEY, a citizen of the United States, residing at Philadelphia, in the county of Philadelphia and State of Pennsylvania, have invented certain new and useful Improvements in Centrifugal Casting Machines, of which the following is a specification.

My invention relates to centrifugal casting machines, and is in some of its general aspects, similar to the construction set forth in my pending application No. 573,019.

An important object in view is to provide a device of this character with means for reliably and yet yieldingly holding the lid and mold in operative engagement with each other during the casting operation, so that the sudden expansion of the mold which inevitably takes place when the mass of molten metal is suddenly poured into it, will not subject the parts to undue strain, and will not, in any way, unfavorably affect the perfect operation of the machine.

Another important object is to employ spring pressure for yieldingly holding the lid and mold together, but with the spring so far removed from the mold that the excessive heat from the mold will not reach the spring and take the temper out of it.

Still another object is to provide a lid having annular slots for the escape of the excess metal poured into the mold.

Other objects will appear in the subjoined description.

An important feature of the invention consists of a revoluble basket having a lid rigidly held thereon against outward movement; and a mold carried inside the basket; and means including a spring for yieldingly holding the mold in engagement with the lid.

The invention consists in certain novel features of construction and arrangement of parts as will be hereinafter described and claimed, reference being had to the accompanying drawings, in which;

Fig. 1 is a sectional view of my device.

Fig. 2 is a front elevation on a reduced scale of the revoluble basket employed.

Fig. 3 is an elevation, on a reduced scale, of the lid employed with the revoluble basket shown in Fig. 2; and,

Fig. 4 is a perspective view of the dog which holds the lid on the basket.

Attention is called in the outset to the fact that centrifugal force has been em-

ployed to yieldingly hold the lids on centrifugal casting machines, which arrangement works very well when the molds are held sufficiently upright to hold the lids in operative position on them by gravity till the machinery is speeded up sufficiently to make the centrifugal mechanism grip the lids. But for the majority of castings the molds should be disposed horizontally in which position gravity will cause the lids to fall off the molds before the machine starts revolving unless other means be provided for holding them in operative position till the centrifugal mechanism has been caused to revolve with sufficient rapidity to grip the lids. With my arrangement, no such difficulty can exist, even when centrifugal force is employed, for in my construction, instead of the lid being held on the mold, the mold is yieldingly held against the lid—is held in a casing which serves as a guide for its movements, so that when a horizontal mold is standing still, the mold will have no disposition to move out of engagement with the lid, but even if it did, the fact that the mold has guided movement relatively to the lid, would cause it to certainly move back into proper engagement therewith, whether pressed by centrifugal force or any other force whatsoever; so that the great advantage of having a stationary lid cooperating with a movable mold becomes quite apparent.

Referring further to the drawings, the numeral 1 indicates a housing having a large central opening 2 at its forward end, and at its inner end an integral sleeve 3 into which is cast a long bearing 4, which supports a hollow shaft 49, having at its inner end inside the housing 1, a heavy flange 48, and beyond the sleeve 3 of the housing, a pulley 58 rigidly held thereon. A basket 41 is rigidly held on the flange 48 by stud bolts 48^a.

The basket 41 carries the cup 42 which is forced out into direct engagement with the lid 43. The basket 41 has pairs of ears 44 which, by means of pivots 45, carry dogs 46 which pass into slots 43^a of the lid to hold the lid on the basket, said dogs being each provided with an integral cross bar 46^a at its outer free end, so that said free ends of the dogs are T-shaped. The lid on each side of the slot 43^a is provided with a slight hump 43^b to prevent the cross bars 46^a from accidental disengagement with the lid.

This lid is also provided with annular slots 47 similar to the slots 17 (shown in the pending application referred to) for the escape of excess metal.

5 I have shown the lid as also provided with an annular inwardly extending flange 43^c which engages the outer end of the cup 42.

The hollow shaft 49 carries the plunger 50. This plunger is operated in one direction 10 by a spring 51, and is also operable in both directions by a hand lever 52 which has an integral upwardly projecting extension 53 at its inner end where it is pivoted to a suitable support 54. This support is rigidly connected to the frame 55 of the machine by means of the bars 55^a, and has a segmental rack 54^a which is engaged by a pawl 52^b carried on the hand lever 52. The section 53 of the hand lever is bifurcated at its upper 15 end to receive the outer projecting end of the plunger, which is provided at its extreme outer end with a nut 56 and a washer 57 which forms a wear plate for said lever section 53.

25 By the arrangement shown a downward movement of the lever 52 will withdraw the plunger from engagement with the mold-carrying cup 42, and the pawl 53^b will hold the lever in its downward position with the 30 plunger thus withdrawn, so that the lid can be easily placed on the mold or removed therefrom.

The operating pulley 58 is rigidly secured on the shaft 49. The operation of my device is as follows:

Assuming that the parts are disassembled, with the plunger 50 forced to its farthest position to the right by the spring 51, the cup 42 is placed in the basket 41; then the 40 lid 43 is secured on the open end of the basket by means of the dogs 46 as already described; the hand lever 52 is elevated to permit the spring 51 to operate with its full force to press the open end of the cup 42 into firm engagement with the lid 43; the machine is then caused to rotate rapidly by means of a power belt passed around the pulley 58; the molten metal is then poured into the mold through the opening 59 at the 50 centre of the lid, which opening is smooth and true, and therefore does not bump or jar the tile spout through which the metal is poured. The metal takes the form of the mold, and if there be any excess metal it 55 passes out through the annular slots 47, and is caught in the casing 1.

As the mold is rapidly revolved preparatory to pouring the molten metal, the air is exhausted from the mold through the openings 47 of the lid, which causes a continuous current of air to be sucked in through the central opening 59. But when the tile spout is entered into this central opening and practically fills it, the suction operates 60 on the molten metal in the spout to draw it

very rapidly into the mold causing it to become more quickly and more evenly distributed over the entire inner surface of the mold, which is a decided advantage.

The pressure of the plunger 50 against 70 the cup 42 yieldingly presses the cup into firm engagement with the lid, so that however much the mold may expand from the heat of the molten metal, or however sudden the expansion may be, the mold and lid will 75 be yieldingly held in firm operative relation to each other by reason of the resiliency of the spring 51. When the metal has been poured and become solidified, the machine is stopped and the spring pressure imposed 80 upon the mold 42 through the plunger 50, is relieved by lowering the hand lever 52, which forces the plunger 50 to the right, in which position it is secured by means of the pawl 52^b; this in turn relieves the pressure 85 against the lid and permits it to be easily removed from the basket; the casting and the mold are then removed from the cup by a pair of expanding tongs, and the casting is jarred loose from the mold, and the parts 90 are ready for the operation to be repeated.

The easy and quick removal of the lid provided for in my device, permits the machine to be operated, time after time, in 95 rapid succession.

Having described my invention, what I claim as new and desire to protect by Letters Patent is:

1. In a device of the character described, 100 a revolving support; a mold carried thereby and having guided movement thereon; a lid and means for rigidly holding the same on the revolving support, said lid having an annular inwardly extending flange adapted to engage the forward end of the mold to form an extension thereof; a plunger carried by the revolving support and adapted to engage the inner end of the mold; and a spring for normally pressing the plunger toward the 110 mold to hold the mold in yielding engagement with the lid.

2. In a device of the character described, 115 a revolving support; a mold carried thereby and having guided movement thereon; a lid and means for rigidly holding the same on the revolving support, said lid having an annular inwardly extending flange adapted to engage the forward end of the mold to form a continuation thereof, said continuation being of an internal diameter to register with the rest of the mold; a plunger carried by the revolving support and adapted to engage the inner end of the mold; and a spring for normally pressing the plunger toward the 120 mold to hold the mold in yielding engagement with the lid.

3. In a device of the character described, 125 a revolving support; a mold carried thereby and having guided movement thereon; a lid 130

and means for rigidly holding the same on the revolving support, said lid having an annular inwardly extending flange adapted to engage the forward end of the mold; a plunger carried by the revolving support and adapted to engage the inner end of the mold; a spring for normally pressing the plunger toward the mold to hold the mold in yielding engagement with the lid; and manual means for holding the plunger in adjusted positions away from the mold against the action of its controlling spring.

4. In a device of the character described, a revolving support; a mold carried thereby and having guided movement thereon; a lid and means for rigidly holding the same on the revolving support, said lid having an annular inwardly extending flange adapted to engage the forward end of the mold to form a continuation thereof; a plunger carried by the revolving support and adapted to engage the inner end of the mold; a spring for normally pressing the plunger toward the mold to hold the mold in yielding engagement with the lid; a manually controlled lever adapted to operate the plunger against the action of its spring, said lever extending rearwardly from the plunger; and a pawl and ratchet cooperating with the lever for holding the plunger in adjusted positions away from the mold against the action of its controlling spring.

In testimony whereof I affix my signature.

WALTER T. JANNEY

In testimony whereof I affix my signature.
WALTER T. JANNEY.
